KARL MEISER, OF NUREMBERG, GERMANY.

ELECTRICAL RING-FURNACE.

No. 806,690.

Specification of Letters Patent.

Patented Dec. 5, 1905.

Application filed April 26, 1904. Serial No. 205,006.

To all whom it may concern:

Be it known that I, KARL MEISER, engineer, residing in Nuremberg, Germany, have invented certain new and useful Improvements in Electrical Ring-Furnaces, of which the following is a clear description.

The chief advantages offered by the ordinary electric furnaces are that the latter allow high temperatures to be obtained and that they are very efficient and can be easily regulated. Notwithstanding these distinguishing features, cases occur sometimes in practice where the use of an ordinary electric furnace would not be advantageous, either from an industrial or from a technical point of view. In such cases the new electric ring-furnace renders excellent services. It consists of a ring-conduit in which several electric ring-furnaces are arranged. Of the latter but one is always in operation, while the other furnaces are being cooled down or subjected to a preliminary heating. This is effected by causing a current of air or of certain gases to circulate in the ring-conduit and to transmit the heat, a similar effect being thus produced, like that obtained in the ordinary gas-heated ring-furnace, based upon the utilization of heated products of combustion.

The new electric ring-furnace can be used in all those cases where good results are realized only when the material to be operated upon is heated very slowly—for example, in the manufacture of incandescent-lamp filaments. The new electric ring-furnace will also find application in the case of all those substances which are not capable of conducting electricity at an ordinary temperature, but become conductive in the presence of higher temperatures. If, for example, raw pressed electrodes for primary batteries were to be burned in an ordinary electric furnace, considerable difficulties would have to be overcome, the unburned electrode mass being nearly a non-conducting substance. In the present electric ring-furnace these difficulties are entirely avoided by subjecting the electrodes to a preliminary heating effect before they are used for conducting the electric current.

The invention is illustrated in the accompanying drawings, in which—

Figure 1 is a plan view. Figs. 2 and 3 are sections on the lines A B and C D of Fig. 1. Fig. 4 is a plan view of a modification. Figs. 5 and 6 are sections on the lines E F and G

H of Fig. 4. Fig. 7 is a plan view of a still further modification. Fig. 8 is a section on line I K of Fig. 7, and Figs. 9 and 10 show a further modification.

Referring first to Figs. 1 to 3, the electrodes *p* and *n*, which convey the current, are arranged at the top and bottom of each chamber 1 2 3, &c. The bottom electrodes remain always in position, while a top electrode is introduced only into that compartment which is just at work—*i. e.*, in the drawings into chamber 2. Chamber 2 is heated by electricity, chambers 8 and 1 are cooled down, chambers 3 4 5 are subjected to a preliminary heating, chamber 6 is recharged, and chamber 7 is emptied. The heat from chambers 8 1 2 is conveyed into chambers 3 4 5 by the circulating air, which enters into chamber 8, flows through chambers 1 2 3 4 5, and when slide *a* is open escapes from chamber 5 into conduit *b*. The latter can be connected with the chimney by means of a similar arrangement like that used in gas-heated ring-furnaces. However, the represented figures show a complete air circulation. It being a fact that while, on the one hand, a gas-heated ring-furnace requires a continuous supply of gas and oxygen, for which products of combustion are let off therefrom in corresponding quantities, the electric ring-furnace allows, on the other hand, a circuitous circulation of the air, which serves here only for conveying heat. In this manner any loss of heat in the chimney is avoided. A further advantage which the described construction has over gas-heated ring-furnaces is that there exists no longer any necessity to draw off the air from the last chamber at the lowest possible temperature. The new furnace allows the air to be drawn off from the last chamber at as high a temperature as 500° and even at higher temperatures, the entire heat which said air contains being passed into the first chamber without waste. The height of the temperature to be used for drawing off depends solely upon what highest temperature the new charge can stand without disastrous effect. In this case the electric ring-furnace with circulatory action has the advantage that only a small number of chambers is required, so that it can be constructed at a small expense. The circulation is obtained through a ventilator provided at *e*, which when slide *a* is open draws off the air from chamber 5 into conduit *b* and forces it from here into conduit *f*. When slide *g* is

open, the air passes from conduit *f* into chamber 8 and flows thereupon in the above-described manner through chambers 8 1 2 3 4 5. Chambers 5 and 8 are separated from the 5 opened chambers 6 and 7 by slides *c* and *d*. As soon as the heating of the charge contained in chamber 2 is completed top electrode *p* is withdrawn and introduced into chamber 3. The further operations of shifting slides *c* and *d*, of closing chamber 6, and of opening chamber 8 cause chamber 6 to be inserted in the circuit and chamber 8 to be put out of circuit, and so on.

In the electric ring-furnace represented in 15 Figs. 4, 5, and 6 the electrodes are arranged horizontally, chambers 6 and 7 are again open, and chambers 8 1 2 3 4 5 are inserted in the circuit. When slide *h* is open, the air-current is drawn by the ventilator 20 from chamber 5 into conduit *i* and then pressed toward chamber 8, the slide *k* of which is also opened. In Figs. 1, 2, 3 a stationary ventilator is used. However, the one required for 25 the construction shown in the following figure is a movable electroventilator capable of being shifted according as the fire progresses. If, for example, chambers 7 8 are opened, the electroventilator is inserted into conduit *f* through aperture *l*, which had been previously 30 closed by a cover, the air being thus drawn off from chamber 6 and passed toward chamber 1.

In order to have the heat effectively transmitted by the air, the walls inclosing the material to be operated upon must of course be 35 as thin as possible. In this connection the fact should also be mentioned that in the electric ring-furnace the material to be treated becomes the hottest part, while in a gas-heated ring-furnace the products of combustion 40 constitute the hottest substance. The circulating air acts, therefore, in the furnace-chamber as a cooling and at the same time also as preserving medium upon the walls. This cooling action can be regulated by means 45 of adjusting the number of revolutions made by the ventilator.

While I have used the term "air" in the foregoing description, any other suitable gas can be used as a bearer of heat. The use of 50 air would of course represent the simplest method. However, it is almost as easy to work with mixtures of nitrogen and carbonic-oxid gas or carbonic acid. These gases may be readily produced by means of throwing 55 some live coal into the new chamber to be inserted. If other gases have to be used for the work, the chamber in question, which is closed at first by a cover and slide, must of course be filled with gas in order to expel all 60 air before said chamber is inserted in the circuit. The joints of the cover and the slide are made close, as usually, by means of clay or the like.

In many cases it is possible by the use of 65 special gases to cause the material to be treat-

ed to be burned in the electric ring-furnace directly without being surrounded by a fire-proof casing. An example which proves this assertion are the electrodes, which when nitrogen and carbonic-oxid are used for obtaining the circulating gas can be burned and treated with graphite without any protecting-case.

Figs. 7 and 8 show a combination of the new electric ring-furnace with the well-known gas-heating ring-furnace. Such combination has the economical advantage that electricity, which is usually expensive, has only to be used for bringing about such increased temperature that can no longer be obtained with the aid of gas. In the figures, *m* is the gas-conduit, whence the gas enters into the furnace-chamber—*i. e.*, into chamber 4 of the figure—when the slides are accordingly opened. The gas is burned in said chamber with the heated air in the same manner as it is done in ordinary gas-heated ring-furnaces. On reaching the highest gas temperature the gas is cut off and the electric current inserted. When heated by electricity, the furnace can work with circuitous air or gas circulation exactly as it 80 has been described heretofore, so that no heat at all is lost hereby in the chimney. To this purpose chimney-slide *n* is closed and ventilator *o* is set to work. When the slides are properly opened, said ventilator draws off the 95 gas from chamber 8 and passes it through conduit *r* into chamber 11. In order that this gas flowing from chamber 8 to chamber 11 may pass over the shortest course, slides *s* in the wind-conduit *m* are closed. In the described combined furnace all the advantages 100 of the electric ring-furnaces are also realized, except that no indifferent gases are used, the latter being provided by the gases of combustion. Attention may finally be called to the 105 arrangement of the electrodes shown in Figs. 7 and 8, which differs from that represented in the other figures. In this case two furnace-chambers are provided for each compartment. They are connected in the bottom 110 by means of a conductor *t*, both electrodes being thus placed above the furnace.

A modified execution is also represented in Figs. 9 and 10, allowing the furnace-chambers themselves to be combined to a ring-conduit. In the latter the material to be treated is arranged alternately with electrodes *p*. Two particular electrodes are connected with the circuit, so that the current circulates between them. The air circulation is as before 120 described.

Having thus described my invention, what I claim is—

1. An electric ring-furnace comprising a ring-conduit, a series of chambers therein, 125 means for electrically heating said chambers, a second conduit, connections between the ring-conduit and said second conduit, slides controlling said connections, a passage leading from the second conduit, connections from 130

said passage to the chambers and slides controlling said connections substantially as described.

2. An electric furnace comprising a ring-conduit, a series of chambers therein, means for electrically heating said chambers, a second conduit, connections between the same and the ring-conduit, slides for controlling said connections, a passage leading from the second conduit, connections from said passage

to the chambers and slides controlling said connections and a ventilator for producing a circulation of air and gas.

In witness whereof I have hereunto set my hand in presence of two witnesses.

KARL MEISER.
